ROY E. GEARHART, OF MARYVILLE, MISSOURI, ASSIGNOR, BY DIRECT AND MESNE ASSIGNMENTS, TO MORE-JONES BRASS AND METAL COMPANY, OF ST. LOUIS, MISSOURI, A CORPORATION OF MISSOURI.

TROLLEY-RETRIEVER.

1,163,139.

Specification of Letters Patent.

Patented Dec. 7, 1915.

Application filed October 29, 1914. Serial No. 869,162.

To all whom it may concern:

Be it known that I, ROY E. GEARHART, a citizen of the United States, residing at Maryville, in the county of Nodaway and State of Missouri, have invented certain new and useful Improvements in Trolley-Retrievers, of which the following is a specification.

This invention relates to trolley retriever mounts and my object is to produce an appliance of this character which will perform its function efficiently and can be re-cocked easily and quickly reset in operative relation to the trolley wire, a further object being to produce a retriever of simple, strong, durable, compact and cheap construction.

With these objects in view the invention consists in certain novel and peculiar features of construction and organization as hereinafter described and claimed; and in order that it may be fully understood reference is to be had to the accompanying drawings, in which:—

Fig. 1, is a side view of a trolley retriever embodying my invention with the trolley pole in operative relation to the trolley wire. Fig. 2, is an enlarged top plan view of the trolley retrieving mount. Fig. 3, is a front view with the trolley pole in section. Fig. 4, is a central vertical longitudinal section, the full lines showing the parts in normal position. Fig. 5, is a similar view with the parts in the position they occupy just as the trigger is about to be re-cocked.

In the said drawings where like reference characters indicate corresponding parts in all the figures, B is a base adapted to be secured upon the top of a car in the customary or in any other suitable manner and resting upon and rotatably secured to the base by means of the pivot stem 1, is a support or frame comprising a horizontal bottom 2, a pair of upwardly projecting ears 3 at the rear corners of the bottom and an upwardly projecting standard 4 at the front end of the bottom, the standard being provided with a vertical slot 5, and constituting a shoulder and guide for the trigger hereinafter described.

Arranged within the frame or support is a trigger tripper of U-shape in side view, consisting of a bottom 6, pivoted at its rear

end at 7 to and between ears 3, and provided at such end with a pair of upwardly projecting arms 8, and at its front end with an upwardly projecting arm 9, provided with a recess 10 to receive a part of the trigger. The bottom of the trigger tripper fits loosely on a vertical pin 11 mounted in the bottom of the support or frame, and a spring 12 is mounted on said pin and is arranged to exert upward pressure thereon and downward pressure on the trigger tripper for the purpose of throwing the latter to the position shown by dotted lines in Fig. 4, for tripping the trigger as hereinafter appears.

Pivoted on a cross pin 13 connecting the upper ends of arms 8 of the trigger tripper is a rock bar 14 carrying a trolley pole 15 in the usual or any preferred manner, which pole is provided as usual with a harp 16 in which is journaled in the customary manner the trolley wheel 17 for engagement with the trolley wire, W.

The upper end of the rock bar carrying the trolley pole is bifurcated and equipped with a cross pin 18, and arranged in said bifurcation is the raised rear end of a trigger 19, the raised end of the same having a longitudinal slot 20 loosely receiving the pin 18. The trigger is provided at its front end in a plane substantially below its rear end, with an arm 21 extending through the recess 10 of the trigger tripper and through the slot 5 of the support or frame, and said arm is provided with a forwardly facing shoulder 22 for normal engagement with the shoulder constituted by the arm 4 of the support or frame. The trigger is also provided rearward of the arm 9 with a pair of laterally projecting ears 23, and extending slidingly through said ears and the arm 9 of the trigger tripper is a pair of rods 24 extending parallel with the trigger, the rear ends of said rods being secured rigidly to the laterally projecting ears 25 of a bar 26 fitting between and pivoted at 27 to the lower end of the rock bar 14 which carries the trolley pole. A pair of coiled expansion springs 28 are mounted upon rods 24 and bear at their opposite ends against the ears 23 of the trigger and adjustable nuts 29, mounted on the rods 24, the latter also carrying the lock nuts 30 to guard against accidental relaxation of the springs 28 due to back turning movement of the nuts 29.

The parts stand substantially as shown in full lines Figs. 1 to 4 inclusive, when the trolley pole is engaged with the wire, the springs 28 being under tension to hold the trolley wheel pressed up against the wire through the rearward pressure applied by bar 26 on the lower end of the rock bar carrying the trolley pole. Should the trolley pole leave the wire, the pressure of the tensioned springs 28 applied through said bar 26 and the rock bar 14, will swing the trolley pole upward as indicated by dotted lines in Fig. 1, the pin 18 moving inoperatively forward in the trigger slot 20.

15 The relaxation of the springs 28 incident to their elevation of the trolley pole to the abnormal height referred to, removes most of the forward pressure of said springs on the trigger, and as a result the latter is instantaneously tripped or unlocked from engagement with the shoulder of the support by the downward movement imparted to the front end of the trigger tripper by the pressure of the spring 12 thereon, it being noted that the downward swing of the front end of the trigger tripper insures the lowering or tripping of the front end of the trigger because the rods 24 extend through both the trigger tripper and the arms 23 of the trigger. The instant this tripping of the trigger is effected, the springs 28 exert sufficient pressure on the trigger to slide the same forward until shoulder 22 is disposed within the slot of the arm or shoulder 4. This sliding action of the trigger is followed by the fall of the trolley pole to a plane below that of the wire, the drop of the pole being limited and cushioned by the springs 28 as the pole in falling imparts simultaneous forward sliding movement to bar 26 and rearward sliding movement to the trigger, the last-named movement being due to the fact that the cross pin 18 comes into engagement with the rear end wall of the slot 20. The entire operation traced is sufficiently rapid to insure the drop of the pole before the car reaches a cross wire unless the car was within a few yards of such a wire when the trolley jumped the wire. The appliance therefore guards against the wreckage of more than one cross wire and usually will avoid the wreckage of any such wire because the dislodgment of a trolley pole usually occurs in rapid travel on a straight course, at the point where the wire is attached to a support carried by a cross wire. Under ordinary travel, however, the striking of the cross wire by the pole will not injure either the wire or the pole because at the time said contact occurs the spring pressure tending to hold the pole upward is relaxed so that the pole is free to swing downward instantly under the resistance of a cross wire which it strikes, this downward movement being practically free until the trolley wheel at

tains a position below the plane of the trolley wire, after which it is checked and cushioned by the engagement of cross pin 18 with the front end of the slot of the trigger, as hereinbefore explained.

In the respect that the pole offers practically no resistance to the cross wire which it encounters, this appliance possesses a decided advantage over the ordinary trolley retriever, as in all of such appliances with which I am familiar, the trolley pole must be pulled down and hence there is an appreciable lapse of time before the trolley pole is depressed within which it may offer a considerable resistance to depression by a cross wire.

To reset the appliance, the trolley pole is pulled downward as usual by a rope (not shown) so that through the engagement of the pin 18 with the front end wall of slot 20, the trigger will be drawn rearward until its shoulder 22 clears the front face of the shoulder of the support, it being noted that at the same time, the springs 28 are released through the forward movement of the trigger and the rearward movement of bar 26. As the shoulder 22 attains the position mentioned, the rearward pull upon the trigger causes the same to swing upward and hence through the rods 24 swing the front end of the trigger tripper likewise against the resistance of spring 12. Relaxation of the pull on the rope is instantly followed by a slight expansion of springs 28, and through this action of said springs the pole starts upward and the trigger is pulled rearward until its shoulder is again in engagement with the shoulder of the support or frame as shown in Fig. 4, the pressure of the springs 28 being sufficient to hold the trigger in such position against any tripping pressure exerted by the relatively weaker spring 12.

The pole is permitted to be pressed up by springs 28 until it is reengaged with the trolley wire when the car is again ready for operation. It is apparent that the support or frame being pivoted on the base B is free to turn to accommodate rounding corners and for reversing the trolley pole at the end of a trip.

From the above description it will be apparent that I have produced a trolley retriever, embodying the features of advantage enumerated as desirable, and I wish to be understood that while I have illustrated and described the preferred embodiment of the same, I reserve the right to make all changes falling within the spirit and scope of the appended claims.

I claim:

1. A trolley retriever, comprising a support, a trigger, a trolley pole, yielding means for simultaneously holding the trigger locked to the support and the pole pressed up,

wardly against a trolley wire, a trigger tripper, a rod pivotally connected to the pole and extending slidably through the trigger and trigger tripper whereby pivotal movement of either shall effect similar movement of the other, and a spring to effect pivotal movement of said trigger and trigger tripper in the event the trolley pole jumps the wire.

10 2. A trolley retriever, comprising a rotatable support, a trigger tripper pivoted thereon, a rock-bar fulcrumed on the trigger tripper, a trolley pole carried by the rock-bar, a trigger having a pin-and-slot connection with the 15 rock bar above the fulcrum point thereof and a shoulder for locking engagement with said support, a bar pivoted to the rock-bar below its fulcrum point and provided with a rod extending slidably through the trigger 20 and the trigger tripper near the free ends thereof, a spring normally holding the trigger pressed forwardly and locked against the support and the said bar pressed rearwardly to hold the trolley pole in operative 25 position, and means exerting pressure to trip the trigger immediately the tension of said spring is relaxed.

3. A trolley retriever, comprising a support provided at its front end with a vertical slot, a trigger tripper pivoted to the rear end of the support for vertical swinging action, a trolley pole pivoted to the rear end of the trigger tripper, a trigger having a pin and slot connection at its rear end with the trolley pole above the plane of the fulcrum point of the latter and extending through said slot of the support and provided with a shoulder, a bar pivoted at its 35

rear end to the trolley pole below the fulcrum point thereof and extending slidably through the trigger and trigger tripper, and a spring mounted on said bar and pressing rearwardly thereon and forwardly on the trigger to normally hold the shoulder of the latter against said support at the upper end 40 45 of the slot of the same.

4. A trolley retriever, comprising a support provided at its front end with a vertical slot, a trigger tripper pivoted to the rear end of the support for vertical swinging 50 action, a trolley pole pivoted to the rear end of the trigger tripper, a trigger having a pin and slot connection at its rear end with the trolley pole above the plane of the fulcrum point of the latter and extending through 55 said slot of the support and provided with a shoulder, a bar pivoted at its rear end to the trolley pole below the fulcrum point thereof and extending slidably through the trigger and the trigger tripper, a spring mounted on 60 said bar and pressing rearwardly thereon and forwardly on the trigger to normally hold the shoulder of the latter against said support at the upper end of the slot of the 65 same, and a spring pressing downward on the trigger tripper and tending to swing the front end of the same and the front end of the trigger downward to effect disengagement between the shoulder of the latter and the said support.

In testimony whereof I affix my signature in the presence of two witnesses.

ROY E. GEARHART.
